UNITED STATES PATENT OFFICE.

PHILIP HAAS, OF DAYTON, OHIO.

HYDRAULICALLY-OPERATED FLUSHING-VALVE MECHANISM.

1,331,706.

Specification of Letters Patent. Patented Feb. 24, 1920.

Application filed August 19, 1919. Serial No. 318,512.

To all whom it may concern:

Be it known that I, PHILIP HAAS, a citizen of the United States, residing at Dayton, in the county of Montgomery and State of Ohio, have invented certain new and useful Improvements in Hydraulically-Operated Flushing-Valve Mechanism; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate an embodiment of the invention selected by me for purposes of illustration, and the same is fully disclosed in the following description and claims.

My invention relates particularly to hydraulically operated flushing valves for water closets in which the opening and closing of the flushing valve mechanism is effected by water pressure. This type of valve mechanism, has heretofore been used to the greatest advantage in buildings where a very high pressure and large volume of water is available for flushing purposes, making it possible to dispense with flush tanks, and effecting the opening and closing of the valve by the pressure of the water, the opening of the valve, the flushing operation, the production of an after fill of the closet bowl, and the final closing of the flushing valve, all being effected in proper sequence by the action of the water pressure without aid or interference by the operator, who merely starts the cycle of operation by pressing a button, or otherwise. It has been found impracticable to use this type of valve mechanism in buildings in which the water supply pipes are of small diameter such as have been commonly furnished in the ordinary private house, and where the pressure of water in the main is comparatively low, for the reason that the required volume of water and the required pressure of this large volume of water was not available, and without it the valve mechanism would not operate correctly, as heretofore constructed. The use of this type of hydraulically operated valve mechanism has therefore been almost entirely limited to office buildings, hotels, apartment houses, and other large buildings, and their use in private dwellings has been negligible.

The object of my present invention is to

provide a hydraulically operated flushing valve mechanism adapted especially for use in private houses and other buildings in which the water supply is conveyed by comparatively small pipes, for example, as small as $\frac{3}{4}$ " in diameter, and in which it may be supplied at comparatively low pressure, to the end that the use of this type of valve mechanism may be extended to the very large class of private dwellings and to secure the accurate predetermined operation of the valve mechanism under all working conditions with the same or greater efficiency than is now obtained in all installations in which the larger supply pipes and higher pressures are available.

In the accompanying drawings,

Figure 1 represents a water closet installation containing an embodiment of my invention.

Fig. 2 is a front elevation of my improved valve mechanism showing the auxiliary cut off cock connected therewith.

Fig. 3 is a central vertical section through the valve mechanism.

Fig. 4 is a vertical section on the line 4-4 of Fig. 3.

Fig. 5 is a front elevation of the main body of the valve mechanism, with the front cover, diaphragm, and flushing valve removed therefrom.

Fig. 6 represents a horizontal section on the line 6-6 of Fig. 3.

Fig. 7 is a detail perspective view showing the several parts of the valve mechanism detached from each other, for greater clearness of illustration.

Fig. 8 is a vertical sectional view of the valve mechanism taken on the plane indicated by the dotted line 8-8 in Figs. 5 and 6.

Fig. 9 is a sectional view of a modified form of cap showing a different means for actuating the relief valve.

In the drawings, 1 represents the main body of the valve mechanism which is preferably made of cast metal and is provided on its front face with a circular flange 2 for the attachment of a closing cap or cover of dome shape, indicated at 3. Within the main body 1 and preferably cast integrally therewith, is a horizontal partition or wall 4, and a vertical transverse wall or partition 5, the latter being provided with a circular opening 6 surrounded on the outer face of the wall 5 by a valve seat 7. The valve

body is also provided with an annular inclined sloping flange portion 8 forming an inclined shoulder or support for the flexible diaphragm, hereinafter described. A comparatively narrow chamber 9 is formed between the vertical wall 5 and the annular flange or shoulder 8, and communicates below the wall 4 with a larger chamber 10, which I term the flushing chamber, the 10 valve body being provided at its lower end with a flushing aperture 11, of large diameter, adapted to be connected to the closet bowl. In this instance I have shown the lower end of the chamber provided with a 15 threaded nipple 12 for the attachment of the flushing pipe 13, indicated in Fig. 1, and leading to the closet bowl 14 which may be of any usual or desired construction.

Within the horizontal and vertical partitions 4 and 5 is formed a second chamber 15 which I term the main water inlet chamber, separated from the flushing chamber by said walls, but communicating therewith through the opening 6 and passage 9, when 20 the flushing valve is open. The valve body is also provided with an outlet aperture, also of large diameter, communicating with the water inlet chamber 15, and adapted to be connected to a closed tank 18 shown in 25 Fig. 1. In some instances this tank is located in rear of the wall or partition adjacent to which the bowl is installed, where it is concealed from view, as shown in Fig. 1, and in some instances it may be necessary to have the tank supported on the outer 30 face of the wall or partition, and for convenience I therefore prefer to provide the valve body with two of these apertures, which I term the tank aperture or apertures, as indicated at 16 and 16^a in the drawings, one located on the rear face of the valve body and the other located on the upper face thereof, one of which is closed by a plug as indicated at 16^b, while the other is 35 connected by pipe 17 with the tank 18, as shown in Fig. 1. Within the chamber 15 or communicating therewith, is an auxiliary water inlet chamber 20 of comparatively small size, and formed in any desired manner, in this instance, the main body of the valve being provided with a boss 19 extending transversely across the rear portion of the body, above the horizontal partition 4, within which the auxiliary inlet chamber 20, 40 is formed, by coring said boss or by boring the same or in any other desired way. I prefer to bore or drill entirely through this boss from one side of the valve casing to the other, and to counterbore the same at 45 one end, to form a recess 51, which is inferiorly threaded to receive the water supply pipe 70, which may be as small as $\frac{3}{8}$ " in diameter, for example, which pipe supplies all the water for flushing purposes, 50 the opposite end of the aperture in the boss

19 being internally threaded, and closed by an adjustable plug 100, which is provided with a notch at its outer end, in order that it may be operated from the outside of the valve body. To insure against leakage, I 70 preferably provide the outer end of this threaded aperture with a closing plug 101 and washer 102 as shown. The front face of the boss 19 is also provided with a discharge aperture 20^a for the auxiliary water 75 inlet chamber 20, which is always in communication with the main inlet chamber 15, and the tank 18. The plug 100 is so arranged that by adjusting it longitudinally of its threaded aperture, it will throttle the 80 discharge aperture 20^a to a greater or less extent.

The front face of the boss 19 within the valve body is provided with a centrally located threaded aperture 21 which receives 85 the threaded inner end of a hollow transfer tube 22, preferably closed at its outer end, and provided with a solid extension 22^a, the outer end of which is threaded, the said 90 transferring tube communicating at its inner end with the auxiliary water chamber 20, and being provided with a laterally arranged discharge aperture 24 located at a point sufficiently removed from its inner 95 end to communicate with the back pressure chamber of the valve mechanism, herein- 100 after described, the said tube extending concentrically through the flushing aperture and through the central aperture formed at the inner edge of the inclined annular shoul- 105 der 8.

25 represents a flexible diaphragm preferably of rubber the marginal portions of which engage the annular flange portion 2 of the valve body, and are held in position 105 by an annular flange portion 26 on the cap 3, which is provided with an angular flange portion 27 to inclose the peripheral edges of the flange 2 of the valve body, providing a neat finish to the valve mechanism. The 110 cap or cover 3 may be held in position with respect to the main body of the valve in any desired way. In this instance I have shown it secured in position by retaining means engaging the outer end of the transfer tube 22, which extends through the cap and is provided with a securing nut 28 and washer 28^a. I prefer this construction, as it dispenses with the use of a number of 115 screws or bolts and enables me to secure 120 a perfectly smooth finish, which contributes to keeping the valve mechanism at all times in a clean and sanitary condition. Within the cap or cover 3 is formed a chamber 29 which I term the pressure chamber, one wall 125 of which is formed by the diaphragm 25, and in this pressure chamber water is accumulated for the purpose of acting upon the diaphragm to close the flushing valve. The cap or cover is also provided with a 130

relief passage 34 controlled by a relief valve 38 operable from the outside of the valve mechanism by means of a push button 39, or any other form of actuating mechanism 5 which may be found convenient, as a pivoted handle. The relief passage 34 communicates with a short tubular nipple 35 extending through the front wall of the valve body, and through a marginal portion of 10 the diaphragm, and leading into the enlarged flushing chamber 10 of the valve body communicating with the bowl 14 so that when the relief valve is opened, the water in the pressure chamber may flow out 15 into the enlarged flushing chamber where it will not encounter any back pressure against it, and thus enabling the pressure chamber to be instantly relieved to permit of the quick and full opening of the flushing valve. 20 The flushing valve proper is carried by the diaphragm 25 and consists of a rubber ring 42 which engages the valve seat 7 and is preferably carried in a metal shell 43 engaging the inner face of the diaphragm, and 25 held in position by a sleeve 44, extending through apertures in the diaphragm, shell, and valve, provided with a flange on the outer face of the diaphragm, and having on its inner end a threaded portion, engaged 30 by nut 45 and washer, for holding the valve and shell in proper position with respect to the diaphragm. When the valve is in closed position, as shown in Figs. 3, and 6, for example, the shell 43 extends through 35 the central aperture at the inner edge of the inclined shoulder 8, which shoulder tends to support the diaphragm and prevent it from injurious distortion. The sleeve 44 is provided with a central aperture which 40 loosely fits around the transfer tube 22, with an easy fit, and the discharge aperture 24 of the transfer tube is so located that it will be uncovered when the valve is in closed position, so as to communicate directly with 45 the pressure chamber, but will be covered by the sleeve 44 when the valve is in open position, and until the valve is within a short distance of its closing position, thereby throttling the discharge of water from 50 the aperture 24 which must pass through the annular space between the tube 22 and sleeve 44. The annular space between the tube 22 and sleeve 44 forms a constant communication between the inlet chamber and 55 the back pressure chamber, whether the flushing valve is open or closed.

Water is supplied to the valve by means of the pipe 70 in which I locate an auxiliary cut off valve 71, see Figs. 1 and 2, in order 60 that the water supply may be cut off entirely for the purpose of cleaning, adjusting or inspecting the valve mechanism, and also for further purposes hereinafter described. The water is admitted through a pipe of small 65 diameter, and is further throttled down by

the fact that the auxiliary inlet chamber 20 is made preferably of smaller diameter than the pipe itself so that there shall be no loss of pressure within the auxiliary inlet chamber. The water passes from the discharge aperture 20^a of the auxiliary water chamber 20 into the main inlet chamber 15, and is again throttled by the small size of the discharge aperture 20^a, thus forcing a portion 70 of the water to pass through the transverse tube 22, and through the annular space between the tube 22 and sleeve 44 into the pressure chamber 29, no matter how low the pressure in the main may be, thus filling the pressure chamber and building up a 80 pressure therein, which acts upon the diaphragm 25, and as the diaphragm is of much greater area than the flushing valve, the said valve will be forced into closed position, shutting off communication between the inlet chamber 15 and the flushing discharge aperture 11. The water continues to flow into the inlet chamber 15, filling the same and flowing up into the tank 18, as soon as 85 the flushing valve is closed, and accumulating in the tank 18, compressing the air therein, until the air pressure per square inch equals the pressure of the water in the main supply pipe 70, when the inflow of water ceases. To effect the flushing operation, it is only necessary for the operator to actuate the relief valve 38 by means of the push button 39, or other actuating means, thereby establishing communication between 90 the pressure chamber and the flushing discharge aperture 11, when the accumulated pressure in the tank acting on the face of the flushing valve, will force the valve to open to its fullest extent, and by means of 95 the large apertures 16, 6, and 11, will deliver 100 a large volume of water rapidly to the bowl 14 for flushing purposes, a much larger volume than could be passed in the same length of time through the main 70, and effect a 105 thorough flushing of the bowl. As soon as 110 the pressure in the inlet chamber 15 is reduced by the opening of the flushing valve, water again begins to flow into the valve from the main 70, the incoming water joining in the flushing action, while a part of 115 the same will be transferred from the auxiliary inlet chamber 20 through the transfer tube 22, and seeping slowly through the aperture 24, and between the tube 22 and sleeve 44, into the back pressure chamber, 120 the relief valve 38 having in the mean time been closed by releasing the push button or other actuating means, pressure immediately begins to accumulate in the pressure chamber, and acting on the diaphragm, the flushing valve begins to close. The flushing action will take place very rapidly until 125 checked by the partial closing of the valve, after which the valve will close more slowly, permitting a portion of the incoming water 130

or water from the tank to trickle through the outlet 6 to the bowl 14, to effect what is termed the after fill, and insuring the bowl and water seal receiving the necessary amount of water in the flushing action, and the closing action of the valve will continue slowly as the pressure builds up in the pressure chamber 29, until the valve 42 is almost seated, at which time the outlet aperture 24 of the transfer tube 22 will be uncovered by the sleeve 44, permitting the water to be transferred more rapidly into the pressure chamber, to insure the final seating of the valve. The uncovering of the outlet aperture 24 of the transfer tube 22 before the valve is completely seated, effects a quick and positive final closing of the valve, and obviates the hissing noise frequently made in the final throttling action of a valve in closing off a supply of water and also prevents the wear of the valve occasioned by the seeping of water past the same where its final closing action is delayed. As soon as the flushing valve is closed, the water again accumulates in the tank 18, from which it has been partially or wholly withdrawn by the flushing action, depending upon the duration of flushing, and the parts return to the normal position, indicated in the drawings, and remain in this position until the valve mechanism is again operated. It will be seen that the flushing valve itself is operated entirely by hydraulic means and therefore cannot be injured or interfered with by the operator, who can only actuate the relief valve of the pressure chamber.

It will be seen that by adjusting the plug 100 hereinbefore described, the discharge aperture 20^a of the auxiliary inlet chamber 20 can be variably throttled, thereby insuring the transfer of water through the transfer tube 22 to the pressure chamber at all times, even though the pressure in the main may be somewhat reduced, and in practice this throttling device can be so adjusted as to further control the duration of the flushing, as obviously the greater the extent to which the aperture 20^a is closed, the more rapidly the water will be transferred to the pressure chamber through the transfer tube 22, and the more quickly the flushing valve will be closed. It will also be seen that the adjustment of the plug 100 can be readily effected from the exterior of the valve casting by removing the closing plug 101 without disassembling the valve or interfering with its operation. It is desirable that the flushing valve shall perform the first portion of its closing movement more or less rapidly and then perform the next portion of its closing movement slowly, in order to allow sufficient water to pass slowly to the bowl, after the flushing operation, to refill the bowl and water seal, so that the valve shall be firmly and positively given its final

closing movement. In some instances it may be found that when the discharge aperture of the auxiliary inlet chamber 20 is throttled by the plug 100 to the required extent, to insure the proper duration of flush, and the positive closing of the valve under all conditions of pressure, even though water may be turned on at another faucet, or at other points in the building connected with the water main, the flushing valve may be forced to its seat too rapidly to allow the necessary time for the after fill. In order to prevent this, I prefer to provide a bypass 80 extending from the recess 51 to an aperture 81 in the annular flange 8 beneath the diaphragm, and extending in this instance through a boss 82, and to provide in said flange one or more openings 83 (two being shown) in said flange, adjacent to the opening 81 communicating with the chamber 9, and thence with the flushing chamber 10. This by-pass allows water entering from the main before entering the auxiliary inlet chamber in which it is slightly throttled, to pass to the opening 81, and discharge through the apertures 83, thus setting up a slight pressure on the diaphragm when the flushing valve has nearly reached its closing position in opposition to the pressure in the pressure chamber, as the diaphragm tends to cover the aperture 81, thus tending to slightly retard the seating of the valve, until the final accumulation of water in the pressure chamber after the uncovering of the aperture 24 in the transfer tube, finally closes the valve and presses the diaphragm upon and over the aperture 81, closing it also. I find that this by-pass is very efficient in retarding the closing movement of the valve sufficiently to allow the after fill to be accomplished without in any way interfering with the positive and certain closing of the flushing valve after the discharge aperture 24 in the transfer tube has been uncovered as before described.

The apparatus herein described is so constructed and designed that it may be readily installed in any dwelling and adjusted to the pressure and volume of the available water supply therein, and it will operate accurately in the manner described regardless of variations in the water pressure which are frequent in dwelling houses having service pipes of small diameter and moderate pressures, and due to the opening of faucets or other use of water at other points in the mains.

Instead of using a push button to actuate the relief valve I may employ a lever or handle as indicated in Fig 9, in which 3^a represents a slightly modified form of cap containing the pressure chamber 29^a and provided with the relief valve 38^a and passage 35^a to communicate with the discharge 130

chamber 10 of the valve as heretofore described. In Fig. 9 I have shown a movable actuating lever 39^a having a disk portion 140 at its inner end engaging a disk 141 on a part connected with the valve stem and held in normally retracted position by a spring 142, said part being provided with a washer 143 to prevent leakage and the parts being held in assembled position by the sleeve nut 144. Obviously a movement of the handle 39^a in any direction will cause the disk 140 to elevate the disk 141 and open the valve. The cap 3^a may be provided with a central aperture 145 to receive the threaded outer end of the transfer tube for attaching the cap by means of this threaded extension and a nut and washer (as shown at 28, 28^a) in the other figures, may be secured to the valve body by screws or in any other desired way.

What I claim and desire to secure by Letters Patent is:—

1. In a hydraulically operated flushing valve the combination of a valve body provided with a tank aperture of relatively large area, a flushing discharge aperture of correspondingly large area, a flushing valve interposed between said tank aperture and flushing discharge aperture, a pressure chamber for closing said valve and holding it in closed position, a relief valve for said pressure chamber, said valve body being provided with a water inlet passage of relatively small area, and an inlet chamber communicating therewith and having a reduced discharge aperture at all times in communication with the tank aperture, and a communicating passage of small area and capacity extending from said inlet chamber to the pressure chamber, whereby the restricted discharge outlet for the inlet chamber insures at all times and under all conditions of pressure, a supply of water to the pressure chamber, to effect the closing of the flushing valve, and to hold it normally closed.

2. In a hydraulically operated flushing valve the combination of a valve body provided with a tank aperture of relatively large area, a flushing discharge aperture of correspondingly large area, a flushing valve interposed between said tank aperture and flushing discharge aperture, a pressure chamber for closing said valve and holding it in closed position, a relief valve for said pressure chamber, said valve body being provided with a water inlet passage of relatively small area, and an inlet chamber communicating therewith and having a reduced discharge aperture at all times in communication with the tank aperture, and a communicating passage of small area and capacity extending from said inlet chamber to the pressure chamber, whereby the restricted discharge outlet for the inlet chamber

insures at all times and under all conditions of pressure, a supply of water to the pressure chamber, to effect the closing of the flushing valve, and to hold it normally closed, and throttling means for partially closing the discharge aperture of the inlet chamber to cause the water to pass more readily to the pressure chamber.

3. In a hydraulically operated flushing valve the combination of a valve body provided with a tank aperture of relatively large area, a flushing discharge aperture of correspondingly large area, a flushing valve interposed between said tank aperture and flushing discharge aperture, a pressure chamber for closing said valve and holding it in closed position, a relief valve for said pressure chamber, said valve body being provided with a water inlet passage of relatively small area, and an inlet chamber communicating therewith and having a reduced discharge aperture at all times in communication with the tank aperture, and a communicating passage of small area and capacity extending from said inlet chamber to the pressure chamber, whereby the restricted discharge outlet for the inlet chamber insures at all times and under all conditions of pressure, a supply of water to the pressure chamber, to effect the closing of the flushing valve, and to hold it normally closed, and an adjustable throttling device for partially closing to a greater or less extent, the discharge aperture of the said inlet chamber.

4. In a hydraulically operated flushing valve the combination of a valve body provided with a tank aperture of relatively large area, a flushing discharge aperture of correspondingly large area, a flushing valve interposed between said tank aperture and flushing discharge aperture, a pressure chamber for closing said valve and holding it in closed position, a relief valve for said pressure chamber, said valve body being provided with a water inlet passage of relatively small area, and an inlet chamber communicating therewith and having a reduced discharge aperture at all times in communication with the tank aperture, and a communicating passage of small area and capacity extending from said inlet chamber to the pressure chamber, whereby the restricted discharge outlet for the inlet chamber insures at all times and under all conditions of pressure, a supply of water to the pressure chamber, to effect the closing of the flushing valve, and to hold it normally closed, and an adjustable throttling device operable from the exterior of the valve body for partially closing to a greater or less extent the discharge aperture of said inlet chamber.

5. In a hydraulically operated flushing valve the combination of a valve body pro-

- vided with a tank aperture of relatively large area, a flushing discharge aperture of correspondingly large area, a flushing valve interposed between said tank aperture and 5 flushing discharge aperture, a pressure chamber for closing said valve and holding it in closed position, a relief valve for said pressure chamber, said valve body being provided with a water inlet passage of relatively small area, and an inlet chamber communicating therewith and having a reduced discharge aperture at all times in communication with the tank aperture, and a communicating passage of small area and capacity extending from said inlet chamber to the pressure chamber, whereby the restricted discharge outlet for the inlet chamber insures at all times and under all conditions of pressure, a supply of water to the pressure chamber, to effect the closing of the flushing valve, and to hold it normally closed, said valve body being provided with a threaded passage extending from said discharge aperture of the inlet chamber to the exterior of the valve body, and a throttling screw located in said passage for throttling said discharge aperture, said screw being operable from the exterior of the valve body.
6. In a hydraulically operated flushing valve mechanism of the kind described, the combination with a valve body provided with a tank aperture of relatively large area, a flushing discharge aperture of correspondingly large area, a normally closed flushing valve interposed between the tank aperture and flushing discharge aperture, a pressure chamber for closing said valve and holding it in closed position and a relief valve for said pressure chamber, of an inlet chamber within the main body, having a discharge aperture of small area in communication with the tank aperture at all times, a transfer tube connected with said inlet chamber, said transfer tube extending into the pressure chamber and being provided with a discharge aperture communicating therewith, for diverting a part of the incoming water to the pressure chamber, said valve body having a water inlet passage communicating only with said inlet chamber.
7. In a hydraulically operated flushing valve mechanism of the kind described, the combination with a valve body provided with a tank aperture of relatively large area, a flushing discharge aperture of correspondingly large area, a normally closed flushing valve interposed between the tank aperture and flushing discharge aperture, a pressure chamber for closing said valve and holding it in closed position and a relief valve for said pressure chamber, of an inlet chamber within the main body, having a discharge aperture of small area in communication with the tank aperture at all

times, a transfer tube connected with said inlet chamber, said transfer tube extending through and having a sliding engagement with an aperture in said flushing valve, and being provided with a discharge aperture in communication with the pressure chamber.

8. In a hydraulically operated flushing valve mechanism of the kind described, the combination with a valve body provided with a tank aperture of relatively large area, a flushing discharge aperture of correspondingly large area, a normally closed flushing valve interposed between the tank aperture and flushing discharge aperture, a pressure chamber for closing said valve and holding it in closed position, and a relief valve for said pressure chamber, of an inlet chamber within the main body, having a discharge aperture of small area in communication with the tank aperture at all times, a transfer tube connected with said inlet chamber, said transfer tube extending through and having a sliding engagement with an aperture in said flushing valve, and having a laterally disposed discharge aperture, in communication with said pressure chamber, normally uncovered when the said valve is in closed position, and so located as to be covered by the said valve when the latter is in open position, to restrict the flow of water to the pressure chamber.

9. In a hydraulically operated flushing valve mechanism of the kind described, the combination with a valve body provided with a tank aperture of relatively large area, a flushing discharge aperture of correspondingly large area, a normally closed flushing valve interposed between the tank aperture and flushing discharge aperture, a pressure chamber for closing said valve and holding it in closed position and a relief valve for said pressure chamber, of an inlet chamber within the main body, having a discharge aperture of small area in communication with the tank aperture at all times, a transfer tube connected with said inlet chamber, said transfer tube extending into the pressure chamber and being provided with a discharge aperture communicating therewith, for diverting a part of the incoming water to the pressure chamber, said valve body having a water inlet passage communicating only with said inlet chamber, and means for throttling the discharge aperture of the said water inlet chamber to facilitate the passage of water through the transfer tube to the pressure chamber.

10. In a hydraulically operated flushing valve mechanism of the kind described, the combination with a valve body provided with a tank aperture of relatively large area, a flushing discharge aperture of correspondingly large area, a normally closed flushing valve interposed between the tank

- aperture and flushing discharge aperture, a pressure chamber for closing said valve and holding it in closed position, and a relief valve for said pressure chamber, of an inlet chamber within the main body, having a discharge aperture of small area in communication with the tank aperture at all times, a transfer tube extending through and having a sliding engagement with an aperture in said flushing valve, and having a laterally disposed discharge aperture, in communication with said pressure chamber, normally uncovered when the said valve is in closed position, and so located as to be covered by the said valve when the latter is in open position, to restrict the flow of water to the pressure chamber, and an adjustable device for variably throttling the discharge aperture of the said inlet chamber.

5 13. In a hydraulically operated flushing valve mechanism of the kind described, the combination with a valve body provided with a tank aperture, of relatively large area, a flushing discharge aperture of correspondingly large area, a normally closed flushing valve interposed between the tank aperture and flushing discharge aperture, a pressure chamber for closing said valve and holding it in closed position, and a relief valve for said pressure chamber, of an inlet chamber within the main body, having a discharge aperture of small area in communication with the tank aperture at all times, a transfer tube connected with said inlet chamber, said transfer tube extending into the pressure chamber and being provided with a discharge aperture communicating therewith, for diverting a part of the incoming water to the pressure chamber, said valve body having a water inlet passage communicating only with said inlet chamber, an adjustable device for variably throttling the discharge aperture of said inlet chamber, and means permitting the adjustment of said adjustable throttling device from the exterior of the valve body without disassembling the parts of the valve mechanism or interfering with the operation thereof.

10 14. In a hydraulically operated flushing valve mechanism of the kind described, the combination with a valve body provided with a tank aperture, of relatively large area, a flushing discharge aperture of correspondingly large area, a normally closed flushing valve interposed between the tank aperture and flushing discharge aperture, a pressure chamber for closing said valve and holding it in closed position, and a relief valve for said pressure chamber, of an inlet chamber within the main body having a discharge aperture of small area in communication with the tank aperture at all times, a transfer tube connected with said inlet chamber, said transfer tube extending through and having a sliding engagement with an aperture in said flushing valve, and having a laterally disposed discharge aperture, in communication with said pressure chamber, normally uncovered when the said valve is in closed position, and so located as to be covered by the said valve when the latter is in open position to restrict the flow of water to the pressure chamber, an adjustable device for variably throttling the discharge aperture of said inlet chamber, and means permitting the adjustment of

15 20 25 30 35 40 45 50 55 60 65 70 75 80 85 90 95 100 105 110 115 120 125 130

said adjustable throttling device from the exterior of the valve body without disassembling the parts of the valve mechanism or interfering with the operation thereof.

- 5 15. In a hydraulically operated flushing valve mechanism the combination with a valve body provided with a tank aperture of relatively large area, a flushing discharge aperture of correspondingly large area, a 10 partition interposed between said apertures and provided with a flushing aperture of correspondingly large area, said main body having also a pressure chamber and a flexible diaphragm forming one wall thereof, a 15 flushing valve carried by said diaphragm for closing said flushing aperture, and holding the valve normally closed, and a relief valve for said pressure chamber, of a water inlet chamber provided with a discharge 20 aperture of relatively small diameter, in communication with the tank aperture, and flushing aperture, a transfer tube extending from the said inlet chamber through an aperture in said valve into and having a 25 discharge aperture in communication with the pressure chamber, said valve body being provided with a water inlet passage communicating with said inlet chamber.
16. In a hydraulically operated flushing 30 valve mechanism the combination with a valve body provided with a tank aperture of relatively large area, a flushing discharge aperture of correspondingly large area, a partition interposed between said apertures 35 and provided with a flushing aperture of correspondingly large area, said main body having also a pressure chamber and a flexible diaphragm forming one wall thereof, a flushing valve carried by said diaphragm 40 for closing said flushing aperture, and holding the valve normally closed, and a relief valve for said pressure chamber, of a water inlet chamber provided with a discharge aperture of relatively small diameter, in 45 communication with the tank aperture and flushing aperture, a transfer tube extending from the said inlet chamber through an aperture in said valve into and having a discharge aperture in communication with the 50 pressure chamber, said valve body being provided with a water inlet passage communicating with said inlet chamber, the discharge aperture of said transfer tube being located in the lateral wall thereof, and in 55 such position as to be uncovered by the flushing valve when the latter is in closed position, and to be covered and throttled by the movement of said flushing valve to open position.
- 60 17. In a hydraulically operated flushing valve mechanism the combination with a valve body provided with a tank aperture of relatively large area, a flushing discharge aperture of correspondingly large area, a 65 partition interposed between said apertures

and providing with a flushing aperture of correspondingly large area, said main body having also a pressure chamber and a flexible diaphragm forming one wall thereof, a flushing valve carried by said diaphragm 70 for closing said flushing aperture, and a relief valve for said pressure chamber, of a water inlet chamber provided with a discharge aperture of relatively small diameter, in communication with the tank aperture 75 and flushing aperture, a transfer tube extending from the said inlet chamber through an aperture in said valve into and having a discharge aperture in communication with the pressure chamber, said valve body being 80 provided with a water inlet passage communicating with said inlet chamber, said flushing valve and diaphragm being provided with a sleeve uniting the same and loosely fitting said transfer tube, and said 85 transfer tube having its discharge aperture in a lateral wall, in position to be uncovered by the said sleeve when the flushing valve is in closed position, and to be covered by said sleeve and throttled when the flushing 90 valve is in open position.

18. In a hydraulically operated valve, the combination with a valve body provided with a water inlet chamber, a tank aperture in communication therewith, a flushing 95 discharge aperture, a flushing valve interposed between said tank aperture and flushing discharge aperture, said valve body being also provided with an annular flange portion, a diaphragm having its marginal 100 portion engaging said annular flange portion and forming one wall of a pressure chamber, said diaphragm being connected with said flushing valve, a cap engaging the marginal portions of said diaphragm and forming the 105 other wall of the pressure chamber, and a relief valve for said pressure chamber, a stationary part secured to the valve body and extending through an aperture in said valve, and means engaging said stationary 110 part for securing said cap to the main body and clamping the marginal portions of the diaphragm between said cap and the annular flange portion of the main body.

19. In a hydraulically operated valve, the combination with a valve body provided with a water inlet chamber, a tank aperture in communication therewith, a flushing 115 discharge aperture, a flushing valve interposed between said tank aperture and flushing discharge aperture, said valve body being also provided with an annular flange portion, a diaphragm having its marginal 120 portion engaging said annular flange portion and forming one wall of a pressure chamber, said diaphragm being connected with said flushing valve, a cap engaging the marginal portions of said diaphragm and forming the other wall of the pressure chamber, and a relief valve for said pressure 125 chamber, and a relief valve for said pressure 130

- chamber, a transfer tube secured to said main body at one end, communicating with said inlet chamber, extending through an aperture in the flushing valve and provided with a discharge aperture within said pressure chamber, normally uncovered when the valve is in closed position, and means engaging said transfer tube for holding said cap in operative position with respect to the 5 valve body, and clamping the marginal portions of the diaphragm between said cap and said annular flange portion of the main body.
20. In a hydraulically operated valve mechanism the combination with a valve body provided with an inlet chamber, a tank aperture communicating therewith, a flushing discharge aperture, a flushing valve interposed between said tank aperture and flushing discharge aperture, a pressure chamber for closing said valve and holding it in closed position, a flexible diaphragm forming one wall of said pressure chamber and operatively connected with said valve, 15 said valve body having a flushing chamber formed therein having a portion of comparatively small area adjacent to the flushing valve, and a portion of larger area adjacent to the flushing discharge aperture, 20 and communicating therewith, a relief passage for said pressure chamber communicating with the portion of said flushing chamber of larger area, and a relief valve controlling said relief passage, and means for establishing a connection at all times 25 between the water inlet chamber and said pressure chamber.
21. In a hydraulically operated flushing valve mechanism of the kind described, the 30 combination with a valve body provided with a tank aperture of relatively large area adapted to be connected with a closed tank, a flushing discharge aperture of correspondingly large area, a flushing valve interposed between the tank aperture and the flushing discharge aperture, a pressure chamber for closing said valve and normally holding it in closed position, and a relief valve for 35 said pressure chamber, of an inlet chamber in said valve body having a relatively small discharge aperture in communication with said tank aperture, means for establishing a constant communication between the said inlet chamber and the pressure chamber, a water supply passage communicating with said inlet chamber, and an auxiliary cut off valve for the water supply passage, whereby said water supply can be cut off, and the relief valve opened to effect 40 the emptying of the tank and the renewal of the air cushion therein.
22. In a hydraulically operated flushing valve mechanism, the combination with a valve body provided with a tank aperture of relatively large area, a flushing discharge 45 aperture of correspondingly large area, a flushing valve interposed between said apertures, a pressure chamber, a flexible diaphragm forming a wall of the pressure chamber and operatively connected to said valve, 50 and a relief valve for said pressure chamber, of an inlet chamber provided with a discharge aperture of comparatively small diameter, in communication with said tank aperture, means for establishing a communication at all times between the said inlet chamber and said pressure chamber to close 55 said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 60
23. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 65 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 70
24. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 75 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 80
25. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 85 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 90
26. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 95 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 100
27. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 105 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 110
28. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 115 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 120
29. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, 125 and a relief valve for said pressure chamber, of an inlet chamber provided with a discharge aperture of comparatively small diameter, in communication with said tank aperture, means for establishing a communication at all times between the said inlet chamber and said pressure chamber to close said flushing valve and hold it normally in closed position, said valve body having an inlet passage communicating with said inlet chamber, and means for temporarily arresting the final closing movement of the flushing valve to insure an after fill of the bowl and water seal of the closet with which the valve mechanism is connected. 130

- tion with said tank aperture, means for establishing a communication at all times between the said inlet chamber and said pressure chamber to close said flushing valve and hold it normally in closed position, said valve body having an inlet passage communicating with said inlet chamber, said valve body having a water discharge aperture communicating with the flushing outlet, and so located as to be closed by the diaphragm when the valve is in closed position, and a by-pass communicating with said inlet passage and inlet chamber, and leading to said aperture to exert pressure on the diaphragm in a direction opposed to that exerted by the water in the pressure chamber, to temporarily arrest the final closing movement of the flushing valve.
25. In a hydraulically operated flushing valve mechanism, the combination with a valve body provided with a tank aperture of relatively large area, a flushing discharge aperture of correspondingly large area, a flushing valve interposed between said apertures, a pressure chamber, a flexible diaphragm forming a wall of the pressure chamber and operatively connected to said valve, and a relief valve for said pressure chamber, of an inlet chamber provided with

a discharge aperture of comparatively small 30 diameter, in communication with said tank aperture, means for establishing communication at all times between the said inlet chamber and said pressure chamber to close said flushing valve and hold it normally in 35 closed position, said valve body having an inlet passage communicating with said inlet chamber, said valve body having a flange portion for engaging and supporting the said diaphragm when the flushing valve is 40 in closed position, said flange portion being provided with an auxiliary discharge aperture adapted to be closed by the diaphragm when the valve is in closed position, and a contiguous aperture communicating with the 45 flushing discharge aperture, said valve body being also provided with a by-pass connected with said auxiliary discharge aperture and communicating with said inlet passage and inlet chamber, to temporarily arrest the final closing movement of the flushing valve.

In testimony whereof I affix my signature.

PHILIP HAAS.
